J. W. Bryant
Attorney

UNITED STATES PATENT OFFICE.

HUGH E. ROBINSON, OF TULSA, OKLAHOMA.

SUCKER-ROD RACK OR HANGER.

Application filed February 12, 1925, Serial No. 8,751. Renewed April 29, 1926.

This invention relates to improvements in sucker rod racks or hangers.

The primary object of the invention is to provide a rack or hanger adapted to support the sucker rods and to hold them in a vertically extending position with said rods entirely free and clear from the rig and ground.

A further object of the invention is to overcome the necessity of laying the sucker rods on the ground or on supports in a horizontally extending position after having been withdrawn from the well while in a vertically extending position, thereby preventing the crystallization of the rods due to being bent or pulled out of alignment during the placing of them on said horizontal support.

A still further object of the invention is to support the said rods in a position clear from the ground so that the danger of the collecting of dirt or other foreign substance upon the rods will be eliminated, thereby preventing the rapid disintegration and wear of the rods and the rapid cutting away of the pumping cups within the well tubing, which is caused by such a collection of dirt and foreign substance.

Another object of the invention is to provide a sucker rod rack or hanger which may be moved easily from one side to the other of the well derrick for causing said rods, while not in use, to be arranged entirely out of the way of the rig, but permitting the said rack or hanger to be moved into a position substantially over the well tubing when a sucker rod is to be replaced.

Other objects and advantages of the invention will be apparent during the course of the following description.

In the accompanying drawings forming a part of this specification and in which like numerals are employed to designate like parts throughout the same,

Figure 1 is a horizontal sectional view of an oil well derrick with the traveling sucker rod rack or hanger properly associated therewith,

Figure 2 is a fragmentary sectional view of the oil well derrick shown in Fig. 1 and further illustrates the traveling sucker rod rack or hanger in elevation.

Figure 3 is a fragmentary top plan view of one end of the sucker rod rack or hanger and one of the tracks upon which the said hanger travels,

Figure 4 is a fragmentary vertical sectional view of one of the hanger supporting tracks with one end of the hanger operatively associated therewith, and

Figure 5 is a fragmentary sectional view of the sucker rod rack or hanger with a sucker rod supported thereupon and further illustrates the means employed for placing and removing a sucker rod in respect to the rack or hanger.

In the drawings, wherein for the purpose of illustration is shown a preferred embodiment of this invention, the numeral 5 designates the legs of an oil well derrick which are connected by the horizontally extending beams 6, the oil well casing being shown and designated by the numeral 7.

Suitably, adjustably bolted to the diametrically opposed beams 6 are the angle brackets 8 which have free arm portions 8^a longitudinally slotted, as best illustrated in Fig. 2 and designated by the reference numeral 9. Adjustably connected to these free arms 8^a of the brackets 8 are the track members 10 which are provided at each end with a right angularly extending arm portion 11 having an elongated slot 12, best illustrated in Fig. 2. These tracks 10 are adjustably connected to the arms 8^a of the angle brackets 8 by means of the bolts 13. The brackets 8 and track 10 are further supported by the shackle bolts 14 which are received within the slots 9 and 12 and are connected to the rods 15 which are intended to have turn buckle structures associated therewith, but not shown in the various figures.

The sucker rod rack or hanger 16 consists of a body portion 17 having an inverted U-shaped end portion 18 at each end thereof which are adapted for being positioned over the tracks 10, as illustrated in the various figures. The closed ends of each U-shaped portion 18 is intended to have a roller 19 journaled therein upon the removable bolt 20 which is threaded to the U-shaped portion as best illustrated in Fig. 4. To prevent the unintentional removal of the U-shaped end portions 18 from the tracks 10, a bolt 21 is removably secured to the opened end of each U-shaped portion 18.

The body portion 17 of this rack or hanger is provided with a plurality of transversely inwardly extending notches 22 which form the said body portion 17 into an equal number of sucker rod seats 23. Projecting upwardly at an angle to the vertical plane of

the body portion 17 are a plurality of arms 24 which are formed with the inclined surfaces 24^a, as best illustrated in Fig. 5. Projecting substantially vertically from each 5 arm 24 is a finger 25. It will now be seen that the fingers 25 and their respective arms 24 form angular seats 26, see Fig. 5, which will be termed elevator holding seats.

In Fig. 5 there is shown a sucker rod 27 10 which is formed with the usual enlargement 28 adjacent the upper end of the same. A hoisting cable 29 is illustrated as having swiveled thereto the hoisting hook 30 detachably connected to the elevator yoke 31 which 15 carries the releasable elevator clamp 32 having the releasing latch 33.

The operation of this sucker rod rack or hanger may be described as follows:—

It will first be considered that a sucker 20 rod is resting upon the rack or hanger 16 with the enlargement 28 engaging a seat 23 formed by a notch 22. To remove this sucker rod 27, as illustrated in Fig. 5, from its seat 23, the releasable elevator clamp 32 25 is mounted upon the rod 27 below the said hanger or rack 16. By drawing upwardly upon the hoisting cable 29, by any suitable hoisting mechanism not shown, the elevator clamp 32 will be moved upwardly upon the 30 rod 27 and will engage the inclined surfaces 24^a of the adjacent arms 24. The upward travel of the elevator clamp 32 along these inclined surfaces 24^a will cause the sucker rod enlargement 28 to travel outwardly upon 35 the upper surfaces of the adjacent arms 24 and between the fingers 25 carried by said arms. The said sucker rod will travel outwardly of these arms until this enlargement 28 is disengaged from the outer ends of the 40 arms when the elevator clamp will entirely support the sucker rod. The sucker rod may then be moved into its proper position for being lowered into the well casing 7. To place a sucker rod upon the rack or hanger 45 16, the elevator clamp 32 is fastened to the same and bears directly against the enlarged portion 28 of the said rod. The rod is moved into a position between two adjacent arms 24 and the rod and elevator is lowered 50 until the elevator rests in the elevator seat 26 formed by the said arms 24 and fingers 25 located upon opposite sides of the notch into which the sucker rod is to be placed. With the elevator clamp 32 resting within 55 its seat 26, the releasing latch 33 may be operated for disconnecting the elevator clamp 32 from the sucker rod 27. After releasing this elevator clamp 32, the sucker rod drops until the enlargement 28 rests

upon the inclined portion 23^a of the sucker 60 rod or hanger seat 23 and it will travel downwardly of its own weight until it is resting upon the said seat 23.

It is to be understood that the form of this invention herewith shown and described is to 65 be taken as a preferred example of the same, and that various changes in the shape, size, and arrangement of parts may be resorted to without departing from the spirit of the invention or the scope of the subjoined claims. 70

Having thus described the invention, I claim:—

1. In a device of the type described, the combination with a well derrick, of a sucker 75 rod rack carried thereby, said sucker rod rack being provided with a plurality of notches for receiving said sucker rods and a plurality of arms carried by said rack for guiding the rods downwardly and laterally into said notches.

2. In a device of the type described, the combination with a well derrick, of a sucker rod rack carried thereby, said sucker rod rack having a plurality of notches formed therein for the reception of sucker rods, a 85 plurality of arms carried by said rack for guiding the sucker rods into said notches, and a finger carried by each arm for forming with its arm a seat to support the sucker rod elevator clamp prior to the releasing of 90 the rod from the clamp.

3. In a device of the type described, a sucker rod rack comprising a body portion, said body portion having a plurality of notches formed therein for receiving sucker 95 rods, and an arm arranged on each side of each notch for guiding a sucker rod downwardly and laterally into the latter.

4. In a device of the type described, a sucker rod rack having a plurality of notches 100 formed therein for providing seats, and means carried by the rack for engaging the enlarged portion of the rod to guide the same in a downward and lateral direction onto one of said seats.

5. In a device of the type described, a sucker rod rack having a plurality of rod receiving notches formed therein, laterally inclined elements carried by the rack and located between adjacent notches for guiding sucker rods into the notches, and a member projecting laterally from each inclined element for forming with the element a seat to support the sucker rod elevator clamp while the rod is being released therefrom.

In testimony whereof I affix my signature.

HUGH E. ROBINSON.
